UNITED STATES PATENT OFFICE.

JOHN F. HEMENWAY, OF NEW YORK, N. Y.

AUTOMATIC PRESSURE-RELEASE FOR CLOTHES-WRINGERS.

1,220,115.

Specification of Letters Patent. Patented Mar. 20, 1917.

Application filed September 9, 1916. Serial No. 119,178.

To all whom it may concern:

Be it known that I, JOHN F. HEMENWAY, a citizen of the United States, residing at New York city, in the county of New York 5 and State of New York, have invented certain new and useful Improvements in Automatic Pressure-Releases for Clothes-Wringers, of which the following is a specification, reference being had therein to the accompanying drawing.

This invention relates to certain new and useful improvements upon my automatic release filed even date herewith, the object being to provide novel means for adjusting the 15 position of the release actuating member in order to enable the releasing device to be set so that the same will be actuated by different thicknesses of material passing through the wringer rolls.

Another object of my invention is to provide a releasing device which is composed of very few parts so arranged that they can be readily placed in position upon an ordinary construction of clothes wringer so that 20 the pressure on the pressure rolls will be instantaneously released when a foreign object is drawn between the same.

Other and further objects and advantages of the invention will be hereinafter set 30 forth and the novel features thereof defined by the appended claims.

In the drawings,

Figure 1 is a side elevation partly in section showing the application of my improved construction of releasing device to a 35 clothes wringer;

Fig. 2 is an end elevation partly broken away to show the manner of mounting the actuated member on the upper pressure roll 40 shaft;

Fig. 3 is a top plan view of a wringer showing the releasing device applied thereto; and

Fig. 4 is a detail perspective view of one 45 of the latch actuated members detached.

Like numerals of reference refer to like parts in the several figures of the drawing.

In carrying out my invention I employ a wringer of the ordinary construction composed of a frame 1 having slotted side bars 2 in which are mounted bearings carrying pressure roll shafts 3 and 4 having meshing gears as clearly shown inclosed by a gear casing 5. The shafts 3 and 4 are provided 50 with pressure rolls 6 and 7, and the upper bearing of the shaft 4 carries coil pressure

springs 8 upon which are mounted bearing plates 9 having depending lugs as clearly shown, said bearing plates being carried by a pressure bar 10. The bearing plates 9 of 60 the pressure bar 10 are engaged by pressure screws 11 carried by a top bar 12 movably mounted within the slotted portions of the side bars 2 and is provided with wear plates 13 at its ends adapted to be engaged by pivoted latches 14 for holding the movably mounted top bar in predetermined position within the frame so that the desired pressure can be obtained on the pressure rolls 65 through the medium of the pressure bars 70 and pressure springs.

The pivoted latches 14 are provided with eyes 15 at their lower ends which register with spaced apertured ears 16 extending laterally from plates 17 secured to the upper 75 end of the side bars 2 as clearly shown in Fig. 2, said apertured ears being spaced from the body of the plate 17 to form a guideway for an actuating stem 18 which is provided with a collar portion 19 having an 80 elongated or oval-shaped opening through which the pressure roll shaft 4 extends, as clearly shown in Figs. 1 and 2. The stem 18 is preferably formed of a channel bar and extends under the cut-away portion 85 formed on the under side of the pivoted latch 14, said latch extending between the flanges of the stem, as clearly shown in Fig. 2, the end of the cutaway portion being formed on an arc of a circle in order to provide 90 a cam face 20 which is adapted to be engaged by the end of the stem so as to throw the pivoted latch outwardly out of the path of the movably mounted top bar so as to release the pressure means. 95

In order to provide means for setting the stem 18 of the collars 19 at the proper distance from the cam portion 20 of the latches, I provide each of the collars with a set screw 21 which is adapted to engage the 100 shaft and hold the end of the stem at the proper distance away from the cam portion of the latch so that the latch will be thrown outwardly out of contact with the top bar when said top pressure roll has moved a predetermined distance upwardly by the passage of material therefrom. It will be seen by this construction by adjusting the set screw 21, the position of the stem of the collar 19 can be determined so that the releasing device can be set in such a manner 105 that the pressure would be released by the 110

passage of different thicknesses of material through the pressure rolls, as by adjusting the set screw so as to raise the stem upwardly, the release will be actuated by the 5 passage of a medium thickness of material, and by adjusting the set screw so as to lower the stem of the collar, the releasing device will not be actuated unless an extremely thick wad of material or foreign object is 10 drawn between the pressure rolls.

In the operation of the pressure release as herein shown and described, the upper pressure roll is free to move vertically a sufficient distance to allow ordinary clothes 15 to be wrung thereby, but when a foreign object is drawn between the pressure rolls the upper roll is lifted such a distance as to throw the stem of the collar into engagement with the cam portion of the pivoted latches so as to force the latches outwardly from off of the wear plates of the top bar which instantaneously allows the top bar to move vertically and releases the pressure means. 20

25 I claim:

1. A clothes wringer, comprising a frame having pressure rolls and pressure means for said rolls, means for normally holding said pressure means in predetermined position, and adjustable means actuated by the vertical movement of one of said pressure rolls for releasing said means. 30

2. A clothes wringer, comprising a frame having pressure rolls and pressure means 35 for said rolls mounted therein, movable members for normally holding said pressure means in predetermined position, and adjustable members carried by the shaft of the upper pressure roll coöperating with 40 said movable members for releasing said pressure means.

3. A clothes wringer, comprising a frame having pressure rolls and pressure means for said rolls, a top bar movably mounted 45 within said frame having pressure screws for adjusting said pressure means, movable members for holding said top bar in predetermined position within said frame, and 50 adjustably mounted members coöperating with said movable members for releasing said pressure means on the separation of said rolls.

4. A clothes wringer, comprising a frame having pressure rolls and pressure means 55 for said rolls, a top bar having means for adjusting said pressure means, movable members carried by the side bars of said frame engaging said top bar for holding 60 said top bar in predetermined position with said frame, and adjustable means actuated by the vertical movement of one of said pressure rolls for moving said movable members out of the path of travel of said top bar. 65

5. A clothes wringer, comprising a frame

having pressure rolls and pressure means for said rolls, movable retaining members for normally holding said pressure means in predetermined position, and adjustable means actuated by the vertical movement 70 of one of said pressure rolls coöperating with said retaining members for releasing the pressure on the pressure rolls.

6. A clothes wringer, comprising a frame having pressure rolls and pressure means 75 for said rolls mounted therein, a top bar movably mounted in said frame having means for adjusting said pressure means, movably mounted latches carried by the side bars of said frame for holding said top bar in predetermined position therein, and members adjustably mounted on the upper pressure roll engaging said movable members for releasing said top bar. 80

7. A clothes wringer, comprising a frame 85 having pressure rolls and pressure means for said rolls, a movably mounted top bar mounted in said frame having means for adjusting said pressure means, plates carried by the side bars of said frame having 90 guideways, latches carried by said plate for holding said top bar in predetermined position within said frame, members adjustably mounted on the upper pressure roll, slidably mounted within the guideways of said 95 plates and engaging said latches for moving said latches out of the path of said top bar on the vertical movement of said pressure roll.

8. A clothes wringer, comprising a frame 100 having pressure rolls and pressure means for said rolls mounted therein, shafts upon which said pressure rolls are mounted, a top bar movably mounted in said frame having means for adjusting said pressure means, pivoted latches carried by the side bars of 105 said frame for holding said top bar in predetermined position within said frame, collars adjustably mounted on the shaft of the upper pressure roll, and stems carried by said 110 collars engaging said latches on the upward movement of said pressure roll for releasing said pressure means.

9. A clothes wringer, comprising a frame having slotted side bars, bearings mounted 115 in the slots of said side bars, shafts mounted in said bearings carrying pressure rolls, a top bar movably mounted in the slotted side bars of said frame, plates carried by the side bars of said frame, latches carried by said 120 plates for holding said top bar in predetermined position within said frame, pressure means mounted in said frame for said rolls, and members adjustably mounted on the shaft of the upper pressure roll engaging 125 said latches for moving said latches out of the path of travel of said top bar.

10. A clothes wringer, comprising a frame having pressure rolls and pressure means for said rolls mounted therein, a top bar mov- 130

- ably mounted within said frame having means for adjusting said pressure means, plates carried by the side bars of said frame provided with guideways, pivoted latches 5 mounted on said plates for holding said top bar in predetermined position within said frame, said latches being provided with cam portions, and members adjustably mounted on the shaft of the upper pressure roll working in said guideways engaging the cam portions of said latches for moving said latches out of the path of travel of said top bar on the upward movement of said pressure roll.
11. A clothes wringer, comprising a frame 15 having pressure rolls and pressure means for said rolls mounted therein, shafts upon which said pressure rolls are mounted, a top bar movably mounted in said frame having means for adjusting said pressure means, 20 pivoted latches carried by the side bars of said frame for holding said top bar in predetermined position within said frame, collars mounted on the shaft of the upper pressure roll, set screws carried by said collar for adjusting the position of said collars thereon, and stems carried by said collars engaging said latches on the upward movement of said pressure roll for releasing said pressure means.
12. A clothes wringer, comprising a frame 30 having pressure rolls and pressure means for said rolls, a movable member mounted in said frame having means for adjusting said pressure means, movable retaining members for holding said movable members in predetermined position within said frame, members carried by the upper pressure rolls for actuating said movable retaining members, and means for adjusting the position of said members in respect to said movable retaining members.
13. A clothes wringer, comprising a frame having pressure rolls and pressure means for said rolls mounted therein, a top bar movably mounted in said frame having 45 means for adjusting said pressure means, movable members mounted on the frame for holding said top bar in predetermined position, and members carrying adjusting screws mounted on the upper pressure roll coacting with said movable members for releasing 50 said top bar.

In testimony whereof I hereunto affix my signature in the presence of two witnesses.
JOHN F. HEMENWAY.
